UNITED STATES PATENT OFFICE.

RUSSELL R. HARGRAVE, OF PASADENA, TEXAS.

RAILROAD-CROSSING SHOCK-ABSORBER.

1,343,869.

Specification of Letters Patent. Patented June 15, 1920.

Application filed March 9, 1920. Serial No. 364,488.

To all whom it may concern:

Be it known that I, RUSSELL R. HARGRAVE, a citizen of the United States, residing at Pasadena, in the county of Harris 5 and State of Texas, have invented certain new and useful Improvements in Railroad-Crossing Shock-Absorbers, of which the following is a specification.

This invention relates to resilient or cushioned crossings for railroads and the like, and is particularly designed for protecting the rails thereof from contact with vehicle wheels and in absorbing the jar and vibration caused by the passage of vehicles over 10 the crossing, or trains over the rails.

Heretofore in the art to which this invention appertains there have been many expedients utilized for grading up approaches to crossings and protecting the 15 rails from contact with vehicle wheels. The majority of such devices are either of such construction, such as wood, that they soon wear out; or else they are formed of concrete or iron which are so rigid in construction 20 that the jar caused by passing trains soon causes the crossing to become broken or else the necessary resiliency of the ties is impaired. The present invention is so designed as to eliminate these undesirable 25 attributes of former crossings by providing a plurality of novelly arranged springs in the crossing body for absorbing shocks, and constructing sections of the crossing body freely movable with respect to each other to 30 prevent disarrangement or breaking resultant from jolts and vibration and to effect a certain resiliency through contact of the 35 wheels of a vehicle passing thereover.

Furthermore, the present crossing is designed so that it may be manufactured and assembled practically complete in order that 40 it may be applied in a very short while and without serious interruption of traffic.

For the purpose of illustrating this invention there is shown in the accompanying drawings one form thereof which is at present preferred, since the same has been found in practice to give satisfactory and reliable results, although it is to be understood that 45 the various instrumentalities of which the invention consists can be variously arranged and organized and that the invention is not limited to the precise arrangement of these instrumentalities as herein shown and described.

In the drawings:

Figure 1 is a plan view of a portion of a railroad crossing having my present invention applied thereto.

Fig. 2 is a sectional end elevation on the 60 line 2—2 of Fig. 1 looking in the direction of the arrow.

Like characters of reference indicate like or similar parts throughout the several views, in which:

A designates the ties of a conventional roadbed to which are secured the rails B. In the present instance the ties A are provided with recesses in which are seated steel supporting plates 1 which extend parallel 70 with each other and with the rails and are disposed between the rails as is clearly illustrated in Figs. 1 and 2. The ties are further provided with other recesses exteriorly of the rails for the reception of substantially 75 L-shaped supporting members 2, also disposed parallel with the rails and adjacent thereto and exteriorly thereof, and having the short flange portions extending vertically to the ties A to lie against and contact 80 with depending flanges 3 of the crossing plates 4 which extend inwardly to a point adjacent the tread of the rails as is shown. Furthermore mounted upon the plates 1 and members 2 are transverse supporting plates 85 1^a which extend beneath the rails as illustrated in Fig. 2. Secured to the supporting plates 1 are a plurality of coil springs 5 which have their upper ends secured to a steel plate 6 which extends the entire width 90 of the crossing and on either side to a point adjacent the tread of the rails as is clearly shown in Figs. 1 and 2. The crossing plates 4 are also spaced from the supporting plate 2 by springs 6 which are arranged in staggered relation longitudinally of the roadbed 95 as is shown in Fig. 1. In order to prevent undue upward movement of the crossing plates 6 and 4 with respect to the supporting plates 1 and 2 a plurality of chains 7 100 are secured to the supporting plates and extend at an angle thereto for engagement with the crossing plates, and also serve to prevent swaying of the crossing plates relative to the supporting plates.

As clearly illustrated in Fig. 2 the crossing plates 4 and 6 extend slightly above the tread of the rails B so that the passage of a vehicle over the crossing will be cushioned and the wheels thereof will not come into 110

contact with the rails. Furthermore, the edges of the crossing plate 6 are beveled as at 8 to prevent possible contact of the rolling stock therewith to disarrange the 5 crossing or derail the train or car.

By forming the vertical flanges of the L-shaped supporting members 2 so that they lie against the depending flanges 3 of the crossing plates 4 earth or gravel may be 10 banked up to lie thereagainst in order to provide a gradual approach to the present resilient crossing.

In laying the crossing the rails B are removed from the ties A and the supporting 15 plates 1 are disposed in the position shown whereupon the transverse supporting plates 1^a are secured thereon and the rails replaced. In applying the present crossing to the usual railroad the same can be disposed in position 20 in its entirety, and in manufacturing the same it may be assembled and applied without the use of peculiar tools or accessories.

In securing the crossing to the ties A bolts 25 9 are used and are driven into the ties with the head portions engaging the supporting plates as clearly illustrated in Fig. 1.

From the foregoing it is thought that the 30 operation and application of the present railroad crossing will be understood but, as many changes could be made in the above construction and many apparently widely different embodiments of this invention could be made without departing from the 35 scope thereof, it is intended that all matters contained in the above description or shown in the accompanying drawings shall be interpreted as illustrative and not in a limiting sense. It is also to be understood that 40 the language used in the following claims is intended to cover all of the generic and specific features of the invention herein described and all statements of the scope of the invention, which, as a matter of 45 language, might be said to fall therein.

I claim:

1. A railroad crossing of the type indicated comprising supporting members, mem-

bers carried above the supporting members constituting a crossing, means for resiliently mounting the crossing members upon the supporting members, and means for preventing swaying and excess movement of the crossing members.

2. A railroad crossing of the type indicated comprising supporting plates, plates carried above the supporting plates constituting a crossing, springs between the supporting plates and crossing plates, and chains connecting the supporting plates with the crossing plates whereby to limit the movement of the crossing plates with respect to the supporting plates. 55

3. A railroad crossing of the type indicated comprising supporting plates engaging the ties, plates carried above the supporting plates constituting a crossing, springs between the supporting plates and crossing plates, chains connecting the supporting plates with the crossing plates 60 whereby to limit the movement of the crossing plates with respect to the supporting plates, and means on the supporting plates and crossing plates for preventing ingress of dirt or gravel from a banked approach 70 to the space between the plates. 75

4. A railroad crossing of the type indicated comprising supporting plates extending parallel with the rails, supporting plates extending transversely to the first supporting plates and disposed with their ends beneath the rails, plates carried above and spaced from the supporting plates constituting a crossing, springs between the supporting plates and crossing plates, angularly disposed chains connecting the first named supporting plates with the crossing plates whereby to limit the movement of the crossing plates with respect to the crossing plates, and coactive means on the supporting plates and crossing plates for preventing ingress of dirt or gravel from a banked approach 80 to the space between the plates. 85

In testimony whereof, I affix my signature hereto.

RUSSELL R. HARGRAVE.
